UNITED STATES PATENT OFFICE.

OLIVER F. HILLPOT, OF EASTON, PENNSYLVANIA, ASSIGNOR TO THE HILLPOT MANUFACTURING COMPANY, OF TRENTON, NEW JERSEY.

VENTILATOR.

No. 893,585.

Specification of Letters Patent. Patented July 14, 1908.

Application filed June 8, 1906. Serial No. 320,826.

To all whom it may concern:

Be it known that I, OLIVER F. HILLPOT, a citizen of the United States, residing at Easton, in the county of Northampton and 5 State of Pennsylvania, have invented a new and useful Ventilator, of which the following is a specification.

This invention relates to ventilators of that general class used beneath the lower 10 sash of a window for the purpose of admitting fresh air into a room.

The principal object of the invention is to provide a ventilator of this type in which three deflecting plates are employed, all arranged to direct the entering current of air in an upward path, one of said plates being adjustable to vary the path of deflection and serving also as a valve to cut off the flow.

A further object of the invention is to provide a device of this type in which the two permanent deflecting plates are disposed at an obtuse angle to each other for the purpose of permitting the entrance of a very large volume of air, and in which the outer or uppermost plate is of sufficient height to prevent the blowing over of a strong current of air and the creation of a draft in the lower portion of the room.

A still further object of the invention is to provide a device of this type in which the movable or valve plate is pivoted at its lower edge and is movable to varying angular positions on both sides of the vertical plane of its axis and which will act in all positions of adjustment, except when fully closed, to direct the current of air in an upward path.

A still further object of the invention is to provide a novel form of friction device for engaging the pivot of the valve plate and maintaining the valve in any position to which it may be adjusted.

With these and other objects in view, the invention comprises the various novel features of construction and combination and arrangement of parts, which will be herein-after more fully described, and pointed out particularly in the accompanying claims.

In the drawings:—Figure 1 is a plan view of a ventilator constructed in accordance 50 with the invention. Fig. 2 is a front elevation of the same. Fig. 3 is a transverse sectional view of the ventilator showing the same in position in a window, the valve plate being partly open. Fig. 4 is a similar 55 view with the valve plate in full open posi-

tion. Fig. 5 is a similar view with the valve closed. Fig. 6 is a detail view of the friction holding device for the valve pivot.

The main frame 1 of the ventilator is preferably rectangular in form and is arranged to fit between the window sill 2 and sash 3. At the ends of the main frame are fitted extension pieces to adapt the ventilator to windows of different widths. In the central portion of the frame is a horizontally elongated opening 5 that is preferably covered by a wire screen 6.

To the inner face of the frame are secured deflecting plates, the lower plate 7 being disposed at a slight angle to the horizontal and the other plate 8 being arranged at a slight angle to the vertical and obtuse angle to the plate 7. This forms a pocket the ends of which are closed by vertical walls 8'. Pivoted within the pocket is a third deflecting plate 9, 75 which also forms a controlling valve, this plate 9 being movable to varying angular positions on both sides of the vertical plane of its pivot. The plate 9 is carried by a rod 10 that extends through openings formed in the 80 end walls 8'. The projecting ends of the rod 10 are each encircled by a coiled spring, the free ends or arms of which are held by pins 12 that are carried by the end walls 8', the pins holding the springs in such manner as to exercise considerable friction on the ends of the 85 pivot rod, so that the valve plate may be held in any position to which it is adjusted.

The valve plate 9 is pivoted at its lower edge at a point adjacent the juncture of the 90 two plates 7 and 8, and is adjustable to any angular position between the full open and full closed positions shown in Figs. 4 and 5, and in any, except the full closed position, the entering current of air will be directed in 95 an upward path by the valve plate. The quantity of air admitted is governed by the extent to which the valve is opened, thus, as shown in Fig. 3, a comparatively small quantity of air can pass between the sash and the 100 adjacent free edge of the valve plate, but the entire volume of air which passes must move upward. When the valve is moved to the full open position, as shown in Fig. 4, a large volume of air may pass, but in this case also 105 the air must take an upward path.

The upper edge of the plate 8 is located at such a distance above the level of the opening 5 that the path of the entering current of air must be deflected before it can reach the 110

top of the plate 8, so that there is no possibility of the air flowing over the top of the plate in such manner as to create a draft in the lower portion of the room.

- 5 It is found in practice that where a single inclined plate is used in the path of a current of air, the air will simply rise up over the plate and will then fall to a greater or less extent, depending on the velocity of the current and the temperature of the room. It is essential, therefore, that at least two deflecting plates be employed, so that the second plate may catch and correct the movement and direct the current into the desired path.
- 10 15 A single plate, moreover, would prove of little or no value if disposed at but a slight angle to the horizontal, and as the angle is raised to more nearly approach a vertical plane, the size of the air passage becomes

more and more restricted and if this is corrected by an increase in the vertical height of the main opening of the ventilator frame, the current of air will invariably flow over the top of the plate.

I claim:—

20 In a ventilator, the combination with an adjustable valve plate, of a pivot carrying such valve plate, and a coiled spring having one or more convolutions surrounding the pivot, and having its free ends secured out of 25 their normal free position whereby a side thrust is exerted on the pivot.

25 In testimony whereof I have affixed my signature, in presence of two witnesses.

OLIVER F. HILLPOT.
